UNITED STATES PATENT OFFICE.

WILLIAM W. DAMPEER, OF WESSON, MISSISSIPPI.

DESIGN FOR A RACK-BAR FOR SASH-LOCKS.

SPECIFICATION forming part of Design No. 29,147, dated August 2, 1898.

Application filed July 11, 1898. Serial No. 685,709. Term of patent 7 years.

To all whom it may concern:

Be it known that I, WILLIAM W. DAMPEER, a citizen of the United States, residing at Wesson, in the county of Copiah and State of Mississippi, have invented and produced a new and original Design for a Rack-Bar for Sash-locks, of which the following is a specification.

This invention relates to a new and original design for a rack-bar for sash-locks; and it has for its object to provide a design of this character that shall be both useful and ornamental.

The leading feature of the design resides in an elongated flat strip provided on one side and at intervals with offstanding upturned hook projections having their straight inner faces lying parallel with the adjacent face of the strip, and in a plane above each of said hook projections with an offstanding oblique downwardly-inclined lip overhanging the hook projection therebelow and having a flat under or inner side meeting the adjacent face of the strip in an acute angle.

The minor features of the design are the hook projections provided with rounded outer faces, the downwardly-inclined lips having compoundly-curved upper faces, and the flat body-strip provided with a single hook projection at its upper terminal and with a single oblique lip at a point near its lower terminal.

In the drawings, Figure 1 is a perspective view of a rack-bar for sash-locks embodying the herein-described design. Fig. 2 is a side edge view thereof.

Referring to the accompanying drawings, the numeral 1 designates an elongated flat strip provided at regularly-spaced points with circular openings 2 therein. The said strip 40 is further provided on one side and at intervals with offstanding upturned hook projections 3, which hook projections are formed with rounded outer faces and straight inner walls 4, which lie parallel with the adjacent 45 face of the strip. In a plane above each of the upturned hook projections 3 the said strip is further provided with a laterally-projecting oblique downwardly-inclined lip 5, which lip projects from the strip a slightly-greater 50 distance than the hook projection therebelow and overhangs the latter, and each of said oblique lips 5 is provided with a compoundly-curved upper face and with a flat under or inner side 6, which meets the adjacent face of 55 the strip in an acute angle. To complete the design, the strip 1 is provided with a single hook projection 3 at its upper terminal and with a single oblique lip 5 at a point near its lower terminal. 60

What is claimed is—

The design for a rack-bar for sash-locks, herein shown and described.

In testimony that I claim the foregoing as my own I have hereto affixed my signature in 65 the presence of two witnesses.

WILLIAM W. DAMPEER.

Witnesses:

WILEY E. OLIVER,
C. E. HARTWELL.
